REFRIGERATING APPARATUS

Clifford H. Wurtz, Dayton, Ohio, John C. Miller, Livermore, Calif., and Leonard J. Mann, Dayton, Ohio, assignors to General Motors Corporation, Detroit, Mich., a corporation of Delaware

Filed Sept. 23, 1958, Ser. No. 762,843

3 Claims. (Cl. 62—419)

This invention pertains to refrigerating apparatus and especially to two compartment household refrigerators in which frost will not collect and remain in either the below- or above-freezing compartments.

It has been customary to place the evaporator in the below- and above-freezing compartments. Such an arrangement not only required frequent defrosting of the evaporator in the above-freezing compartment but also heavy coats of frost formed on the evaporator and all the articles and packages in the below-freezing compartment. More recently, it was appreciated that if the evaporator were outside of the below- and above-freezing compartments and air was circulated from the below- and above-freezing compartments in heat transfer relation with the evaporator and thence returned to the compartments, no frost would collect and remain in either compartment.

It is an object of this invention to provide a simple, inexpensive household refrigerator requiring only a single evaporator and a minimum of ductwork in which frost will not collect and remain in either the below- or above-freezing compartment and which will provide rapid ice freezing.

It is another object of this invention to provide a simple, inexpensive household refrigerator requiring only a single evaporator in which all frosting and defrosting takes place on an evaporator located so that the minimum of ductwork will be required.

It is another object of this invention to provide a simple, inexpensive household refrigerator in which the frost formed on the evaporator surfaces when melted during defrosting will flow into and cool the above-freezing compartment.

It is another object of this invention to provide a simple, inexpensive household refrigerator in which a single evaporator is located between the bottom of the below-freezing compartment and the top of the above-freezing compartment and is in heat transfer with separate air circuits cooling each compartment.

These and other objects are attained in the form of household refrigerator shown in the drawings in which a vertically finned evaporator is located beneath and in contact with the bottom of the below-freezing compartment and has a drip pan beneath forming the top of a horizontal duct at the top of the above-freezing compartment. Separate fans are provided for each compartment. A first air circuit is provided for withdrawing air from the below-freezing compartment at the front thereof and conveying the air between the bottom thereof and the drip pan through the single evaporator to a fan in the rear wall which returns the air to the below-freezing compartment through openings at the upper rear thereof. The above-freezing compartment has a false top wall providing a horizontal duct beneath the drip pan. A second fan in the rear wall of the above-freezing compartment draws air from the compartment between this false wall and the drip pan and returns it through an opening in the rear wall to cool the above-freezing compartment. The evap-

2

orator is provided with an electric heat defrosting means. Defrost water from this evaporator flows onto the false top wall of the above-freezing compartment and down the rear wall thereof to tubing carrying it to a place of disposal.

Further objects and advantages of the present invention will be apparent from the following description, reference being had to the accompanying drawings wherein a preferred embodiment of the present invention is clearly shown.

In the drawings:

Figure 1 is a vertical sectional view of a household refrigerator embodying one form of our invention; and

Figure 2 is a fragmentary vertical sectional view through the drain pan, drain, and liquid trap.

Figure 1 shows a household refrigerator having an upper below-freezing compartment 20 provided with an insulated door 22. Below the below-freezing compartment is an above-freezing compartment 24 provided with an insulated door 26. Between the two compartments is a horizontal cross fin evaporator 28 which rests upon a drip pan 30 which forms the bottom of the upper portion of the cabinet. Resting on top of this evaporator 28 is a removable bottom wall 32 which is therefore in good heat transfer relation with the top of the evaporator 28. This wall 32 is suitable for supporting ice trays 33 for the quick freezing of ice cubes. The space occupied by the evaporator 28 between the drip pan 30 and the bottom wall 32 constitutes a first air passage forming a part of the first air circuit which includes the below-freezing compartment 20 having outlet openings 34 adjacent the door 22 which provide communication with a duct 36 extending as a collar around the front portion of the casing 38 over the opening 34.

The casing 38 surrounds the top and sides of the compartment 20 and joins with the drip pan 30 to provide a substantially sealed compartment. The duct 36 discharges into the first passage between the drip pan 30 and the bottom wall 32. The air flows from the bottom of the duct 36 through the evaporator 28 which occupies the first passage. At the rear of the compartment 20 is a removable shroud 40 which guides the air into the impeller 42 of a centrifugal fan driven by an electric motor 44. The impeller 42 and the motor 44 are removably mounted in an opening in the rear wall of the cabinet 46. The opening is sealed by a diaphragm 48 of an elastomeric material clamped by the clamping ring 50 to the flange 52 of the outer rear wall 54 to seal the opening. Between the motor 44 and the impeller 42 is an insert 56 of foamed plastic. This insert 56 fits into a recess provided in the discharge shroud 58 surrounding the impeller 42. This discharge shroud 58 conveys the air expelled by the impeller 42 to the rear air inlets 60 provided in the rear wall 62 of the compartment 20. The casing 38, the duct 36, the breaker strip 37 and the shroud 58 are enclosed in insulation 63 which is cast or foamed in place.

The fins of the evaporator 28 are provided with notches above and below for receiving the upper and lower portions 64 and 66 of a sheathed electric heater. The drip pan is provided with a drain pipe outlet 68 at its lowest point which extends downwardly into a cup 70 forming a liquid trap. The drain tube 68 is provided with an electric heater section 72 and the cup 70 is provided with a heater section 74. A heater section 76 is also provided beneath the impeller 42 within the shroud 58. A plastic breaker strip 78 is provided between the bottom wall 32 and the shroud 40. The heater sections 72, 74 and 76 are electrically connected to be energized coincidentally with the heater sections 64 and 66 during a defrosting period.

The above-freezing compartment 24 is enclosed within a liner 80 having an outlet opening 82 at the front of the

top wall and a return opening 84 at the rear of the top wall. Above the top wall of the liner 80 beneath the drip pan 30 there is provided a thin layer of insulation 86, the top surface of which slopes downwardly to the rear. Between the insulation 86 and the drip pan 30 there is provided a second horizontal passageway 88. The front and rear ends of the passageway are provided in the foam insulation 135 and 137. At the rear of the liner 80 there is provided a shroud 90 for conducting air from the return opening 84 to the opening 92 in the rear wall communicating with the interior of the impeller 94 of a centrifugal fan driven by an electric motor 96 which extends through an opening in the rear wall 54. Surrounding the impeller 94 is a discharge shroud 98 which conducts the air discharged from the impeller to the opening 121 in the rear wall of the liner 80. The shroud 98 and the liner 80 are enclosed in foam insulation 139. The circulation of air from the above-freezing compartment 24 through the opening 82, the passage 88, the shroud 90, the impeller 94, the discharge shroud 98 and the opening 20, cools the above-freezing compartment 24.

Frost will not accumulate in either of the compartments. However, frost will accumulate on the evaporator 28. Therefore, periodically, the evaporator is heated by the electric heater sections 64 and 66 and at the same time, the heater sections 72, 74 and 76 are energized to melt the frost which accumulates at these points. The melting frost will flow down through the drain tube and fill and overflow the cup 70. This defrost water will flow down the rearwardly sloping upper surface of the insulation 86 and pass through the opening 84 and be carried downwardly by the shroud 90. The shroud 90 is provided with an outlet opening 123 at the bottom which allows the defrost water to flow down the back wall of the liner 80. At the bottom rear of the liner 80 there is provided a discharge tube 125 which extends to some means for disposing of the defrost water.

The evaporator 28 is supplied with liquid refrigerant from a liquefier which includes a sealed motor compressor unit 127 which withdraws evaporated refrigerant from the evaporator 28 through the suction conduit 129 and compresses the refrigerant and forces the compressed refrigerant into the condenser 131 for liquefaction. The resulting liquid refrigerant is conducted through a capillary supply tube 133 to the evaporator 28. The system is arranged to operate the evaporator 28 at a temperature of about -5° to -10° F. during the normal operation of the system. The refrigeration system is shut off during defrosting. Defrosting is accomplished rapidly enough that no thawing will take place within the below-freezing compartment 20 and the above-freezing compartment is prevented from rising above desirable refrigerating temperature for any substantial period.

While the embodiment of the present invention as herein disclosed constitutes a preferred form, it is to be understood that other forms might be adopted.

What is claimed is as follows:

1. A refrigerator having means forming an upper below-freezing compartment and an above-freezing compartment beneath the upper compartment and a first air passageway extending from the front to the rear of said upper compartment between the bottom of the upper compartment and the top of the compartment beneath having a front inlet and a rear outlet connecting with the interior of said upper compartment to form a first air circuit, an evaporating means entirely beneath said upper compartment and entirely in said air passageway having air passages, said upper compartment having a bottom wall extending over and in heat transfer relation with said evaporating means and forming a confining wall of said first air passageway, a second air passageway out of communication with said first passageway and first air circuit extending from front to rear across the top of said above freezing compartment beneath and in heat transfer relation with said first passageway having a front inlet and a

5 rear outlet for cooling said above-freezing compartment, a metal separating wall between and separating said first and second air passageways and separating said second air passageway from said evaporating means, and a second fan means for circulating air from said above-freezing compartment through said second passageway out of communication with but in heat transfer relation with said first passageway through said metal separating wall for cooling said above-freezing compartment.

2. A refrigerator having means forming an upper below-freezing compartment and an above-freezing compartment beneath the upper compartment and a first air passageway extending from the front to the rear of said upper compartment between the bottom of the upper compartment and the top of the compartment beneath having a front inlet and a rear outlet connecting with the interior of said upper compartment to form a first air circuit, an evaporating means in said air passageway having air passages, said upper compartment having a bottom wall extending over and in heat transfer relation with said evaporating means and forming a confining wall of said first air passageway, fan means for circulating air from said upper compartment through said inlet and said first air passageway in heat transfer relation with said evaporator and through said outlet back to said upper compartment, said first air passageway and said first air circuit being out of communication with but in heat transfer relation with said compartment beneath to keep said compartment beneath at refrigerating temperatures, a second air passageway out of communication with said first passageway and first air circuit extending across the top of said above freezing compartment beneath and in heat transfer relation with said first passageway for cooling said above freezing compartment, a metal separating wall between and separating said first and second air passageways and separating said second air passageway from said evaporating means, a second fan means for circulating air from said above freezing compartment through said second passageway out of communication with but in heat transfer relation with said first passageway through said metal separating wall for cooling said above freezing compartment, means for defrosting said evaporating means, and means for conveying the defrost water through said second air passageway and thence into heat transfer relation with said above freezing compartment.

3. A refrigerator having means forming an upper below-freezing compartment and an above-freezing compartment beneath the upper compartment and a first air passageway between the bottom of the upper compartment and the top of the compartment beneath having an inlet and an outlet connecting with the interior of said upper compartment to form a first air circuit, an evaporating means entirely beneath said upper compartment and entirely in said air passageway and having air passages, said upper compartment having a bottom wall extending over and in heat transfer relation with said evaporating means and forming a confining wall of said first air passageway, said first air passageway being provided with a drip pan beneath said evaporating means, said pan having its lower face exposed, a second air passageway extending from front to rear directly beneath the lower face of said pan, a wall at the top of said above-freezing compartment separating said compartment from said second air passageway, said drip pan separating said second passageway from the evaporator, said wall having a front opening communicating with said above-freezing compartment and a rear opening, a shroud connecting with said rear opening and being located in said above-freezing compartment, means for defrosting said evaporating means, said drain pan being provided with a drain and drain trap for draining defrost water therefrom onto said wall, said wall being provided with means for conducting defrost water through said second air passageway from said drain to said shroud, a fan associated with said shroud for circulating air from said above-freezing compartment through said second air passageway and into said above-freezing compartment.

partment through said second air passageway in contact with the lower face of said pan and in heat transfer with said defrost water and back to said above-freezing compartment, said shroud having a drain for draining the defrost water therefrom.
